(57) **CLAIM**

The ornamental design for damper lever flange for grand piano, as shown and described.

DESCRIPTION

FIG. 1 is a front view of damper lever flange for grand piano. FIG. 2 is a right side view of damper lever flange for grand piano.

FIG. 3 is a left side view of damper lever flange for grand piano.

FIG. 4 is a top view of damper lever flange for grand piano.

FIG. 5 is a bottom view of damper lever flange for grand piano.

FIG. 6 is an additional front view defining cross sectional planes 7—7 and 8—8;

FIG. 7 is a cross section view thereof, taken a long line 7—7;

FIG. 8 is a cross section view thereof, taken along line 8—8;

FIG. 9 is a top view defining cross sectional plane 10.

FIG. 10 is a cross section view thereof, taken along line 10—10; and,

FIG. 11 is a rear view of damper lever flange for grand piano. The broken lines are included for the purpose of defining cross section planes and forms no part of the claimed design.
